Augustus Conradt of Philadelphia Penn.
Letters Patent No. 2475, dated Oct. 2, 1866.
Design for a Spoon Handle

Des 2475

The schedule referred to in the Letters Patent and making part of the same.

To all whom it may concern:

It is known that I, Augustus Conradt of the City of Philadelphia in the State of Pennsylvania, have originated and designed a new ornamental Design for the Shank Handle of a Spoon or Fork, or other articles for table use, of which the following is a full, clear and exact description, reference being had to the accompanying drawing, making a part of this Specification.

A, B, represents a silver spoon having the ornamented shank handle, made with its shank, a', b', in a hexagonal form in its transverse section. The ornamental design consists of a series of small projections, c, c, c, formed, or attached along each of the exterior angles of the said shank a', b', as represented in the drawing.

Having thus fully described my invention or production, what I claim as my invention and desire to secure by Letters Patent is, The ornamental Design for the shank handle of a spoon or Fork, or other similar articles for table use substantially as hereinafter set forth and shown.
